(57) **CLAIM**

I claim the ornamental design for a food identification device, as shown and described.

DESCRIPTION

FIG. 1 is a front perspective view of a food identification device showing my new design;

FIG. 2 is a rear perspective view thereof;

FIG. 3 is another front perspective view thereof;

FIG. 4 is a left side elevation view thereof;

FIG. 5 is a bottom plan view thereof; and

FIG. 6 is a rear elevation view thereof;

FIG. 7 is a top plan view thereof; and,

FIG. 8 is front elevation view thereof.
